[57] **CLAIM**

The ornamental design for a blade brake, as shown and described.

DESCRIPTION

FIG. 1 is a front elevational view of the blade brake showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view of the device illustrated in the prior Figure.

The cable of the claimed design has an indeterminate length. Thus, portions of the cable have been omitted for ease of illustration.
